UNITED STATES PATENT OFFICE.

ELWIN R. HYDE AND RICHARD C. HORNER, OF SPRINGFIELD, MASSACHUSETTS, ASSIGNORS TO THE SPRINGFIELD GLUE AND EMERY WHEEL COMPANY, OF SAME PLACE.

MACHINE FOR GRINDING PLANE SURFACES.

SPECIFICATION forming part of Letters Patent No. 416,109, dated November 26, 1889.

Application filed August 13, 1888. Serial No. 282,681. (No model.)

To all whom it may concern:

Be it known that we, ELWIN R. HYDE and RICHARD C. HORNER, of Springfield, in the county of Hampden and Commonwealth of Massachusetts, have invented a new and useful Improvement in Machines for Grinding Plane Surfaces, of which the following is a specification, reference being had to the accompanying drawings, forming part thereof.

Our invention relates to that class of abrading-machines in which are comprised one or more revolving abrading wheels or tools, and a work-support for exposing the surface of the article operated upon to the action of said wheels or tools for the purpose of reducing said surface to a uniform plane, and it has especial reference to machines of this class in which the work-support is itself revolved in a plane at a right angle to the plane of revolution of the abrading wheels or tools.

The object of our invention is to increase the effective abrading capacity of such machines, and also to combine therewith means whereby the adjustments of the several parts of the machine itself and the introduction of work thereto and its removal therefrom will be greatly facilitated and expedited.

To this end our invention consists in a machine comprising an abrading medium which has both a revolving and a reciprocatory movement and a plurality of revoluble work-supports mounted upon a common revoluble bed, whereby each of said work-supports can be moved to a position where the work carried thereby will be exposed to the action of the abrading medium.

Our invention furthermore comprises certain details of construction hereinafter fully described, and particularly pointed out in the claims.

Referring to the drawings, in which like parts are designated by like letters in the several figures, Figure 1 is a side elevation of the machine, looking toward the left in Fig. 2. Fig. 2 is a front elevation thereof. Fig. 3 is a vertical longitudinal section of the front portion of the frame of the machine and of the work-supporting devices. Fig. 4 is a plan view of the mechanism for reciprocating the

cross-head which carries the abrading medium. Fig. 5 is a similar view of the mechanism for revolving the work-holding table, the outlines of the tables and their supporting-bed being indicated by broken lines. Figs. 6, 6^a, 6^b, 6^c, and 6^d are detail perspective views of the devices by which the abrading medium is adjustably supported. Fig. 7 is a view in perspective of one of the revolving tables which support the work. Fig. 8 is a cross-section thereof, taken upon line 8 8 of Fig. 7. Fig. 9 is a view in perspective of one of the jaws of the work-holding clutches. Fig. 10 is a vertical section thereof, taken upon line 10 10 of Fig. 9.

The letter A designates the frame of the machine, which frame terminates at the front end in a vertical cylindrical hub A', and at its rear end in an upright and slightly-overhanging arm A², which arm and hub support, respectively, the abrading and work-holding mechanisms. Frame A is preferably made hollow in form to lessen its weight, and also to enable that portion thereof lying in front of arm A² to be utilized as a reservoir for water when the abrading medium is of the "wet-grinding" class, which reservoir is designated by the letter A³ in Fig. 3.

As herein shown, the abrading medium is composed of two emery wheels B B' of a corresponding diameter, which have a common revolving and laterally-reciprocating movement and a common vertical adjustment, and in addition to such common movements each of said wheels is preferably provided with means whereby it can be independently adjusted both vertically and laterally. The means shown for securing these various movements of the abrading medium will be first described.

The upright arm A² of the frame, which preferably curves slightly toward the front end of the frame, terminates in a vertical face of considerable area, as shown, and projecting from said face are two vertical ribs a, the outer edge of each of which is undercut, as shown in Fig. 4.

The letter C designates a head-block, in the rear side of which is a vertical groove c, hav-

ing undercut edges to receive the outer edges of the ribs a on arm A^2 , and thus retain the head-block upon the arm in such manner as to permit free vertical movement of the former. By making two ribs a upon the arm, instead of a single rib of the full width of groove c , the wearing-surface of said parts is materially reduced without weakening the connection between them.

15 Head-block C is provided at each end with arms $c' c^2$, projecting horizontally therefrom, the front faces of which arms are flush with the front face of the block, and the rear faces of which are preferably provided with strengthening-ribs c^3 , as shown.

Projecting from the front face of the head-block and its arms is a rib c^4 , extending at a right angle to the groove c in the rear face of the block, the edges of which rib are undercut to receive the undercut edges of a groove d in the rear side of a cross-head D , whereby said cross-head is retained and permitted to have free lengthwise movement upon said block. Said cross-head D (shown in detail in Fig. 6^a) is preferably slotted, as shown at d' , for the greater portion of its length, and is provided at its front side with a longitudinal rib d^2 , having undercut edges to receive the edges of a groove e in the rear faces of two corresponding plates $E E'$, and thereby adjustably retain said plates upon the cross-head.

Right and left hand screws $d^3 d^4$ (see Fig. 6^b) are mounted in a block d^5 , seated in the end of cross-head D and retained therein by means of screws d^6 , as shown, or in any other convenient manner, said screws being provided with collars upon each side of said block, whereby they are adapted to have a free revolving movement therein without endwise progression. Each of the plates $E E'$ is provided upon its rear side with a projecting threaded hub e' , which hubs, when the parts are assembled, project within the slot in the cross-head and receive, respectively, the threaded portions of screws $d^3 d^4$, whereby, by turning said screws by means of a wrench or permanent handle, said plates $E E'$ can be adjusted independently toward and away from each other upon said cross-head. Upon their front sides each of the plates $E E'$ is provided with a vertical rib e^2 , having undercut edges to receive the edges of vertical grooves f in the rear sides of two wheel-heads $F F'$, one of which heads is shown detached in Fig. 6^c. Adjusting-screws f' , mounted in upwardly-projecting brackets f^2 on said wheel-heads in such manner as to revolve without endwise progression, are tapped into the plates $E E'$ at their lower ends, and are preferably provided with the usual handles f^3 at their upper ends, as shown. By means of said screws f' either of the wheel-heads can be independently adjusted in a vertical direction upon the plates $E E'$. Projecting from the front side of each of the wheel-heads $F F'$ are two arms f^4 , containing bearings for one

of the shafts B^2 , which carry the abrading-wheels $B B'$, respectively. One of said abrading-wheels is suitably secured to the inner end of each of said shafts B^2 , and upon each of said shafts, between its bearings f^4 , is secured a band-pulley b , by which revolving movement is transmitted to said shafts and abrading-wheels from a suitably-arranged counter-shaft.

It will be observed that by the means just described provision is made for independently adjusting the abrading-wheels both laterally and vertically, the former adjustment being for the purpose of gaging the distance between said wheels according to the width or diameter of the work to be operated upon, and the latter adjustment being for the purpose of compensating for unequal wear of said wheels by slightly depressing the one which wears away most quickly, should it become necessary to do so.

In addition to the two independent adjustments, the wheels $B B'$ have a common laterally-reciprocating movement with the cross-head upon head-block C , and also a common vertical movement with said head-block upon arm A^2 of the frame, as hereinbefore stated, and to the means for producing such common movements attention is next directed.

Upon the rear sides of arms $c' c^2$ of head-block C are secured by screws, as shown, or in any suitable manner threaded hubs c^5 , which hubs receive, respectively, right and left hand threaded vertical screw-shafts C' , which shafts are mounted at their lower and upper ends in bearings c^6 upon each side of the frame of the machine. At their upper ends said screw-shafts carry bevel-gears c^7 , and mounted in bearings upon the top of arm A^2 is a cross-shaft C^2 , carrying at each end bevel-gears c^8 , which mesh with said gears c^7 , and thereby transmit the motion of one of said screw-shafts to the other in a well-known manner. The screw-shaft upon the right side of the frame, as seen in Fig. 2, is continued nearly to the bottom of the frame and carries at its lower end a bevel-gear c^9 , which meshes with a bevel-gear c^{10} upon the rear end of a horizontal shaft C^3 , mounted in suitable bearings upon the side of the frame. Said shaft C^3 extends to or nearly to the front end of the frame and at its front end is squared to receive a wrench, as shown, or may be provided with a suitable hand-wheel to enable said shaft to be revolved manually. Revolution of shaft C^3 will, through the arrangement of the gears and the cross-shaft, as just described, impart a similar movement to both screw-shafts C' in opposite directions, and by the movement of the threaded hubs c^5 upon said screw-shafts head-block C , the cross-head, and wheels $B B'$ will be raised or lowered upon arm A^2 as said shaft C^3 is turned in one or the other direction. In order to counterbalance said block and the parts carried thereby, and thus render the vertical adjustment thereof, as just described,

very easy, we connect one end of a rope or chain c^{11} thereto by means of an eye c^{12} , secured to the head-block midway between the ends of the latter, and conduct said rope or chain over two pulleys c^{13} , mounted in brackets secured to arm A^2 , to the interior of said arm, where suitable weights are suspended thereon, as shown by broken lines in Fig. 1. The object of the common vertical adjustment of wheels $B B'$, thus effected, is for the purpose of lowering said wheels upon and raising them from the work, and also to regulate their grinding action upon the surface of the work, and by the means just described a very delicate vertical adjustment of said wheels can be made with perfect ease.

The lateral reciprocating movement of wheels $B B'$ is produced as follows: A horizontally-extending bracket G is rigidly secured to arm A^2 of the frame near its upper end, which bracket is provided with bearings g for a horizontal worm-shaft G' , carrying worm g' and cone-pulley g^2 . (See Fig. 4.) Said bracket is also provided with bearings g^3 for a vertical shaft G^2 , the upper end of which shaft passes loosely through said bearings and through a worm-gear g^4 , which is mounted between said bearings, and which meshes with worm g' . A spline-and-key connection between shaft G^2 and worm-gear g^4 , as shown, compels said shaft and gear to revolve in unison, while permitting the former to move vertically within the latter. Said shaft G^2 is mounted at its lower end in a bearing h of a bracket H , secured to the rear side of arm c^2 of head-block C by screws passing through said bracket into a pad formed upon said arm, as shown by broken lines in Fig. 4, or in any other convenient manner. Collars are secured upon said shaft above and below said bracket H compel the former to follow the vertical movements of the latter as head-block C is moved up or down, and to the lower end of said shaft is secured a gear-wheel g^5 , which meshes with a similar gear-wheel g^6 , secured to the lower end of a short vertical shaft G^3 , mounted in a bearing h' in said bracket H . At its upper end said shaft G^3 carries a crank-disk g^7 , having a crank-pin g^8 adjustable toward and away from the center of said disk by a screw g^9 , in the usual manner. A link g^{10} connects said crank-pin with cross-head D , as shown in Figs. 2 and 4. Motion being communicated to worm-shaft G' from a suitably-arranged counter-shaft through a belt and cone-pulley g^2 , said shaft will, through worm g' , gear g^4 , shaft G^2 , and gear-wheels $g^5 g^6$, impart a uniform revolving movement to shaft G^3 and crank-disk g^7 , and the latter, through link g^{10} , will impart a horizontal reciprocating movement to the cross-head and wheels $B B'$, the amount of which reciprocating movement can be accurately gaged by the adjustment of crank-pin g^8 . The abrading-wheels $B B'$ receive their revolving movements by means of belts connecting their pulleys b with a counter-shaft,

which belts will preferably be led over intermediate idler-pulleys, which are free to move lengthwise of their shafts, to enable the belts to follow the reciprocating movements of said wheels. By means of the compound revolving and reciprocating movement of the abrading-wheels thus secured their capacity for quickly reducing the surface of the work is greatly increased; but this desirable result is still further increased by the revolving movement which is imparted to the work itself in a plane at a right angle to the plane of revolution of said wheels, and to the means devised by us for supporting, and thus revolving, the work attention is now directed.

As hereinbefore stated, one of the objects of our invention is to combine with the means for holding and operating the abrading medium, as shown and described, a plurality of revolute work-holding mechanisms, each of which can be moved to a position to present the surface of the work held thereon to the action of the abrading medium. By thus providing two or more of such work-holding mechanisms we are enabled to greatly expedite the operation of the machine, inasmuch as new work can be secured upon and finished work removed from those that are idle at the same time that the abrading medium is operating upon the work held by the one which is in operation. For the purpose of illustrating this feature of the invention we have shown two of these work-holding mechanisms, which are constructed as follows:

The letters I I designate two circular tables carried at the upper ends of short shafts i , said tables having the usual intersecting-slots, T-shaped in cross-section, within their upper surfaces, and having concentric bearing-surfaces i' on their lower surface, as shown in Figs. 7 and 8. The shafts i of said tables are mounted in vertical bearings within and upon opposite sides of the center of a bed K , which bed is mounted upon hub A' of the frame by means of a tubular stud k , projecting within said hub, as shown in Fig. 3, whereby said stud serves as a pivot about which as a center the bed is free to revolve horizontally. As shown, the bed is substantially oval in outline, and is provided upon its upper surface with concentric bearing-surfaces k' , corresponding to those upon tables I, and is preferably provided around its edge with an upwardly-extending flange k^2 . The upper surface of the bed, with the exception of the horizontal bearing-surfaces k' , preferably slopes gradually and downwardly from its edge toward its center, where it is provided with an opening extending through stud k , as shown in Fig. 3, whereby the water used with a wet-grinding abrading medium, which falls upon said bed, is caused to seek said central opening in the latter and descends therethrough into the reservoir in frame A. The tables I are provided with downwardly-extending annular flanges i^2 , which overlap the edges of the outer concentric bearing-sur-

faces k' of the bed, as shown, and prevent the water, particles of emery, &c., from working between the respective bearing-surfaces of the tables and bed, thereby avoiding a common cause of injury to said surfaces.

Upon the upper surfaces of tables I are clutches for engaging and holding the work. Said clutches preferably consist of two or more jaws I', (see Figs. 9 and 10,) composed of a lower member, which is secured to the table by bolts with T-shaped heads located within the slots in the table, and an upper member movably secured upon said lower member and adjusted thereon by a screw i^3 , which is mounted in a bearing on the lower member and enters a nut secured to the upper member. We have shown the working-faces of the jaws of said clutches as being formed upon the arc of a circle and concentric with the centers of the tables, thereby adapting them for use in connection with circular work; but it will be understood that said working-faces will be formed to correspond with the character of work upon which the machine is to be used.

Upon the lower ends of shafts i of the tables and beneath bed K are secured corresponding worm-gears i^4 , collars i^5 being located upon said shafts between said gears and the lower surface of the bed, to insure steadiness of movement to the shafts.

The letter L designates a worm-shaft, which is mounted at one end in a bearing l , pivotally secured to a bracket L', projecting from frame A, in such manner that said bearing is free to turn horizontally upon its pivot. Near its opposite end said shaft L is supported by a bearing l' , secured to a plate l^2 , which plate rests upon a pad formed upon frame A, to which it is secured by bolts l^3 , passing through slots l^4 in the plate, whereby said plate is permitted to have a limited sliding movement toward and away from hub A' of the frame. Shaft L at its free end carries a worm l^5 , which is adapted to mesh with one of the gears i^4 of tables I when plate l^2 occupies its forward position, but which is moved to a position to clear said gear when said plate is moved to its rearmost position. Near its opposite end said shaft is provided with a band-pulley l^6 , by which motion is transmitted to said shaft from a counter-shaft through a belt.

It follows from the construction just described that when either of the gears i^4 is in mesh with the revolving worm l^5 its table I and the work held thereon will be given a uniform revolving movement in a horizontal plane, and it follows, furthermore, that by moving said worm to a position to clear said gear the bed K can be revolved about its pivot to bring the opposite gear and table beneath wheels B B'.

It is essential that means be provided for locking the bed to prevent movement thereof while the abrading medium is operating upon the work carried by either of the tables I, and we have combined means for this purpose

with the means for shifting plate l^2 and worm l^5 in such manner that both functions are performed by a single lever. Said lever (designated by the letter M) is pivoted at m to the side of frame A, its short arm extending upwardly to the plane of bed K and its long arm extending to the front end of the frame, where it terminates in a suitable handle, as shown. To the end of the short arm of said lever is pivotally connected the rear end of a bolt m' , sliding within a sleeve m^2 , secured to the side of arm A'. Bed K is provided at each end with a socket k^3 to receive the front end of said bolt, so located upon said bed that when either of the tables I is directly beneath wheels B B' one of said sockets will be opposite the end of said bolt. By moving lever M from the position shown by broken lines in Fig. 1 to that shown by full lines bolt m' will be thrust forward to cause it to enter one of the sockets on the bed, and by moving said lever in the opposite direction said bolt will be withdrawn from its engagement with the bed. A lever N, pivoted at one end to frame A, as shown in Fig. 5, is connected at its opposite end by means of a link n to the short arm of lever M, and between its ends by means of a link n' to plate l^2 . It follows, therefore, that the same movement of lever M which withdraws bolt m' from engagement with the bed will withdraw worm l^5 from mesh with either of the gears i^4 , and, conversely, that the same movement of said lever which restores said worm to mesh with one of said gears will project said bolt into one of the sockets of the bed, and thus rigidly hold said bed from movement. A standard m^3 , secured to the frame adjacent to the end of the long arm of lever M, is provided in its side next to said lever with a notch, as shown in Fig. 2, to receive the latter and retain it in the position shown by broken lines in Fig. 1 whenever it may be desired to do so.

As the abrading-wheels bear with a heavy pressure upon the work, and as the latter is supported upon bed K at one side of the central support of said bed, we provide the bed at each end with a downwardly-projecting bearing k^4 , in which is journaled an anti-friction roll k^5 , and provide frame A with a shoulder a' , upon which one of said rolls bears, as shown in Figs. 1 and 3, in each operative position of the bed. By this means the downward pressure upon the bed during the operation of the abrading-wheels upon the work is distributed between shoulder a' and hub A', and undue strain upon the bed is avoided.

When the abrading-wheels employed are of the class known as "wet-grinding" wheels, we design to utilize a small centrifugal or other pump to raise water from the reservoir in frame A and carry it through suitably-arranged pipes to the surface of the wheels, whence it passes to the bed, and from thence back into the reservoir, as previously described. A constant circulation of the same water is thus effected, which is especially ad-

vantageous in locations where it is not convenient to connect the machine with water supply and escape pipes. We have not shown said pump and water-conducting pipes, for the reason that their use is common to all of our wet-grinding machines, and because they form no part of our present invention.

For the purpose of affording access to the reservoir, the frame is provided with an opening a^2 , which opening is normally closed by a cover, as shown in Fig. 3. Access to arm A^2 of the frame is also afforded by a door a^3 (shown in Fig. 2) in case it should be desirable to enter said arm for any purpose.

15 The operation of the machine thus constructed is as follows: Presuming band-pulleys b , b , g^2 , and l^2 to be connected by belt with the same or different counter-shafts, whereby revolving movement is transmitted 20 to wheels B , B' and worm-shafts G' and L , wheels B , B' are adjusted laterally by means of screws d^3 , d^4 , to locate them at the proper distance apart with respect to the width or diameter of the work to be operated upon, 25 the work itself is firmly clamped between the clutch-jaws of one of the tables I, bed K is manually revolved to move said table and work beneath the abrading-wheels, lever M is moved to project bolt m' into the adjacent 30 socket of said bed and also to move worm l^5 into mesh with the gear i^4 of said table, and the machine is set in operation. The revolving and laterally-reciprocating abrading-wheels are now lowered upon the 35 work by turning shaft C^3 , and are regulated as to their abrading action upon the surface of the work by means of said shaft, as hereinbefore described. The work itself being revolved in a plane at a right angle to the 40 plane of revolution of the abrading-wheels, the latter very rapidly reduce the surface of the former, and the lateral reciprocating movement of the wheels causes the surface operated upon to be a true plane. When two 45 abrading-wheels are employed, as shown, they will preferably be of different degrees of coarseness, so that one of them will perform the function of a finishing-wheel, and should one of said wheels wear away more rapidly 50 than the other it can be depressed to compensate for such wear by means of its screw f' . Either of the wheels B , B' , moreover, can be moved by one of the screws d^3 , d^4 to a position where it will be entirely clear of the work 55 whenever it is desired to use but one of said wheels, thus enabling the machine to operate as a single-wheel machine. While the abrading-wheels are thus operating upon the work carried by one of the tables I, new work can 60 be clamped upon the idle table ready to be moved under the wheels as soon as they have completed their first operation, whereby a great saving in time in feeding work to and removing it from the machine is effected. 65 Bed K is balanced upon hub A' of the frame in such manner that it can be revolved upon said hub with but slight exertion; but, if de-

sired, any suitable anti-friction devices can be employed to increase its freedom of movement.

Having completed the operation upon the first piece of work, wheels B , B' are elevated slightly by turning shaft C^3 , lever M is moved from the position shown by full to that shown by broken lines in Fig. 1, bed K is revolved 70 to move the second table I beneath the wheels, said lever M is restored to its former position and wheels B , B' are lowered upon the new work, and the operation proceeds as before. The operation would be the same were the 80 bed provided with more than two tables I, each being moved under the abrading-wheels in regular sequence.

The work for which the machine herein shown and described is especially designed is 85 the grinding of the annular bearing-surfaces of valve-bodies and other similar circular work, in which the wheels B , B' operate at diametrically-opposite points upon the surface of said work; but it is adapted to operate 90 equally well upon flat surfaces generally.

While we have shown and described the abrading medium as consisting of emery-wheels, it will be understood that we do not thereby wish to limit ourselves to the use of 95 such material, as it is obvious that the particular abrading material employed is not essentially related to the construction and operation of the machine itself. It is obvious, furthermore, that various modifications of the 100 details of the construction shown and described can be made without departing from the spirit of our invention.

Having thus fully described our invention, what we claim, and desire to secure by Letters Patent, is—

1. The machine for grinding plane surfaces herein described, comprising, in combination, a revolving and laterally-reciprocating abrading medium and a plurality of revoluble 110 work-supports mounted upon a common revoluble bed, whereby each of said work-supports can be moved to a position to present the surface of the work carried thereby to said abrading medium, substantially in the 115 manner and for the purpose described.

2. The machine for grinding plane surfaces herein described, comprising, in combination, a revolving and laterally-reciprocating abrading medium, a revoluble bed having its plane 120 of revolution at a right angle to that of said abrading medium, a plurality of revoluble work-supports mounted upon said bed, each of which work-supports is provided with a worm-gear, and a worm-shaft mounted in 125 movable bearings, whereby the worm carried thereby can be moved into and out of engagement with the gears upon said work-supports, arranged and operating substantially in the manner described.

3. In a machine for grinding plane surfaces, the combination of the following instrumentalities, viz: a substantially-horizontal frame terminating at one end in an upright arm, a

head-block secured to and vertically adjustable upon said arm, a horizontally-movable cross-head mounted upon said head-blocks, a wheel-head adjustably secured to said cross-head, said wheel-head having journaled thereon a shaft carrying an abrading-wheel, a crank-shaft having link-connection with said cross-head, whereby revolution of the former will produce a reciprocating movement of the latter, a worm-shaft carrying a band-pulley, intermediate gear-connections between the worm upon said shaft and said crank-shaft, and a revolving work-support mounted upon said frame beneath the plane of said abrading-wheel, arranged and operating substantially as set forth.

4. In a machine for grinding plane surfaces, a substantially-horizontal frame terminating at one end in an upright arm, a vertically-adjustable head-block mounted upon said arm, a longitudinally-reciprocating cross-head carried by said head-block, two vertically and horizontally adjustable wheel-heads mounted upon said cross-head, a shaft carrying an abrading-wheel and a band-pulley journaled in each of said wheel-heads, a bed mounted upon a vertical axis upon said frame, and a plurality of revolving work-supports mounted upon said bed, arranged and operating substantially as set forth.

5. In a machine for grinding plane surfaces, frame A, having upright arm A² at one end thereof, head-block C, adjustably mounted upon said arm, cross-head D, mounted to slide transversely upon said head-block, said cross-head being slotted, as shown at d', and having adjusting-screws d³ d⁴, mounted to revolve without endwise progression in one end thereof and extending into said slot, plates E E', movably mounted upon said cross-head, each of said plates having a nut e', extending into the slot in the cross-head and receiving one of said screws d³ d⁴, wheel-heads F F', vertically movable upon said plates E E', respectively, adjusting-screws f', mounted upon said wheel-heads and tapped at one end in said plates, and shafts B², each carrying a band-pulley and an abrading-wheel journaled in said wheel-heads, arranged and operating substantially as described, whereby provision is made for independently adjusting said wheel-heads both vertically and horizontally upon said cross-head, in combination with bed K, revolvably mounted upon said frame, and tables I, revolvably mounted upon said bed, substantially as set forth.

6. In a machine for grinding plane surfaces, frame A, having arm A² at one end thereof, head-block C, supporting the revolving and laterally-reciprocating abrading medium and having a vertically-sliding connection with said arm A², threaded hubs c⁵, secured to said head-block, vertical screw-shafts C' C', having right and left hand threads engaging the threads in said hubs, each of said shafts having at its upper end a bevel-gear c⁷ and one of said shafts having at its lower end a bevel-

gear c⁹, cross-shaft C², having at each end bevel-gears c⁸, meshing with the gears c⁷ of said screw-shafts, and horizontal shaft C³, having at one end bevel-gear c¹⁰, meshing with the gear c⁹ at the lower end of one of said screw-shafts and having its opposite end provided with suitable means whereby it can be revolved manually, combined and operating substantially as and for the purpose described.

7. In a machine for grinding plane surfaces, frame A, having at one end upright arm A², supporting the abrading medium and having at its opposite end cylindrical hub A', bed K, resting upon said hub and having a central stud k, projecting within the latter, a plurality of work-supporting tables I, mounted upon said bed by means of short vertical shafts i, passing through the latter and carrying worm-gears i⁴ at their lower ends, a worm-shaft L, mounted at one end in a pivoted bearing l and near its opposite end in a bearing l', secured to a sliding plate l², said shaft carrying band-pulley l⁶ and worm l⁵, and means, substantially as described, for moving said plate l² toward and away from hub A', combined and operating substantially as described, whereby said worm can be moved into and out of engagement with either of the worm-gears connected with said work-supporting tables.

8. In a machine for grinding plane surfaces, the combination, with frame A, having revolvably-mounted thereon bed K, carrying tables I, said tables having vertical shafts i and worm-gears i⁴ at the lower ends of said shafts, of a locking device on said frame to engage said bed and prevent movement thereof, sliding plate l², mounted upon said frame and supporting one end of worm-shaft L, carrying worm l⁵, a lever, as M, fulcrumed upon said frame, and intermediate connections, substantially as described, between said lever, sliding plate l², and the locking device, whereby movement of said lever will impart movement to said plate and locking device simultaneously, substantially as and for the purpose set forth.

9. In a machine for grinding plane surfaces, the combination, with frame A, bed K, having a horizontal revolving movement upon said frame, and tables I, having a horizontal movement upon said bed, of worm-gears i⁴, operatively connected with said tables, worm-shaft L, mounted at one end in a pivoted bearing l and near its opposite end upon sliding plate l², elbow-lever M, pivoted upon the side of frame A, locking-bolt m', connected at its rear end to the short arm of said lever, sockets k³ upon bed K, to receive the front end of said bolt, lever N, pivoted at one end to frame A, link n, connecting the opposite end of said lever with the short arm of lever M, and link n', connecting said lever N between its ends with sliding plate l², arranged and operating substantially as and for the purpose set forth.

10. In a machine for grinding plane surfaces, frame A, having at one end upright arm A² and shoulder a', and at its opposite end hub A', of bed K, centrally pivoted upon 5 said hub, said bed having the work-supporting tables I, mounted thereon, between its center and its edge, and having at its outer edge and opposite each of said tables downwardly-extending brackets k⁴, in which are 10 journaled anti-friction rolls k⁵, one of which rolls rests upon said shoulder a' of the frame whenever either of said tables I occupies its operative position, combined and operating substantially as and for the purpose set forth.
- 15 11. In a machine for grinding plane surfaces, hollow frame A, having at one end upright arm A² and at its opposite end cylindrical hub A', communicating with reservoir A³ in said frame, in combination with bed K, having a central tubular stud k, projecting 20 within said hub A', said bed having an upwardly-extending flange k², extending around its outer edge, a central opening communicating with the bore of stud k and horizontal annular bearing-surfaces k', and having its 25 upper surface, with the exception of said bearing-surfaces, inclined downwardly from the edge to the central opening thereof, and tables I I, supported upon the bearing-surfaces of said bed, substantially as and for the 30 purpose described.
